US00D918989S

(12) **United States Design Patent** (10) Patent No.: **US D918,989 S**
Au et al. (45) Date of Patent: **** May 11, 2021**

(54) **CAMERA LENS COVER**

(71) Applicant: **GoPro, Inc.**, San Mateo, CA (US)

(72) Inventors: **Heman Au**, San Mateo, CA (US); **Huy Phuong Nguyen**, San Mateo, CA (US); **Matthew David Thomas**, Castro Valley, CA (US)

(73) Assignee: **GoPro, Inc.**, San Mateo, CA (US)

(**) Term: **15 Years**

(21) Appl. No.: **29/706,014**

(22) Filed: **Sep. 17, 2019**

(51) LOC (13) Cl. **16-05**

(52) U.S. Cl.

USPC **D16/237**

(57) **CLAIM**

The ornamental design for a camera lens cover, as shown and described.

DESCRIPTION

FIG. 1 is an upper perspective view of a first embodiment of a camera lens cover of our new design;

FIG. 2 is a lower perspective view of thereof;

FIG. 3 is a front view thereof;

FIG. 4 is a rear view thereof;

FIG. 5 is a right view thereof;

FIG. 6 is a rear view thereof;

FIG. 7 is a top view thereof;

FIG. 8 is a bottom view thereof;

FIG. 9 is a cross-sectional view thereof; and,

FIG. 10 is an upper perspective view thereof in an environment of a camera.

FIG. 11 is an upper perspective view of a second embodiment of a camera lens cover of our new design;

FIG. 12 is a lower perspective view of thereof;

FIG. 13 is a front view thereof;

FIG. 14 is a rear view thereof;

FIG. 15 is a right view thereof;

FIG. 16 is a rear view thereof;

FIG. 17 is a top view thereof;

FIG. 18 is a bottom view thereof;

FIG. 19 is a cross-sectional view thereof; and,

FIG. 20 is an upper perspective view thereof in an environment of a camera.

FIG. 21 is an upper perspective view of a third embodiment of a camera lens cover of our new design;

FIG. 22 is a lower perspective view of thereof;

FIG. 23 is a front view thereof;

FIG. 24 is a rear view thereof;

FIG. 25 is a right view thereof;

FIG. 26 is a rear view thereof;

FIG. 27 is a top view thereof; and,

FIG. 28 is a bottom view thereof.

Broken lines formed by equal length dashes (dash-dash lines) represent unclaimed portions of the camera lens cover and form no part of the claimed design. In FIGS. 10 and 20, broken lines formed by equal length dashes further represent unclaimed environment of a camera to which the camera lens cover is attached and form no part of the claimed design.
